COIN CONTROLLED SAVINGS CLOCK

Application filed November 14, 1929, Serial No. 407,134, and in Sweden February 3, 1928.

Our invention relates to coin controlled savings clocks in which the clockwork is normally locked and may be released for operation by insertion of a coin or coins. The principal object of the invention is to simplify the mechanism and render its functioning certain and easy. Another object is to so construct and arrange the clockwork release mechanism that it may also serve as a counting or indicating device.

An embodiment of the invention is illustrated in the accompanying drawings, in which Fig. 1 is a side elevational view of a fragment of the device, sufficient of the clockwork being shown to render the construction and operation of the invention clear; Figs. 2 and 3 are details; Figure 4 is a side elevational view of the means for frictionally engaging the driving wheel of the clock movement with the coin control mechanism.

1 indicates the coin chute, into which the coins as usual are inserted through an opening 2 in the upper part of the clock-case. The main part of the chute extends vertically, so that the coins immediately fall to the bottom 20 of the case by gravity. A disk 3 is journaled on a shaft 4 at the side of the chute. The disk is slowly turned clockwise by the clockwork, but is also movable relative to the clockwork by means of the fact that the disk is pressed against a driving-wheel 21 forming part of the clockwork by a spring 3^a. The edge of the disk 3 is provided with a recess 5, in which a two-armed lever 7, which is slightly pressed against the edge of the disk by means of a spring 6 (or its equivalent), engages with the recurved end 8, when the recess comes opposite the hook-like end 8 of the lever. Fig. 1 shows the lever in the said engaged position. The lever 7 when in this position holds the clockwork locked, for instance by a small plate-spring 9 at the upper end of the lever engaging a pin 10 of the balance of the clockwork. By means of a swingable release lever 11, an escapement-pawl 12 influenced by a plate-spring 27, and an escapement-wheel 13, which is rigidly connected with the disk 3, the latter is turned counter clockwise when a coin falls through the chute. The release lever 11 is journaled on a pin 14 close to the chute 1 in such a way, that a toe 15 on the lever extends somewhat into the chute through an opening 16 in the chute wall, so that the lever is moved aside by the falling coins. Thus each time that a coin falls down through the chute 1 the wheel 13 and the disk 3 are turned back a step, i. e. one tooth 22. If at that time the bottom end 8 of the lever 7 engages the recess 5 of the disk 3 (Fig. 1), it will be pushed out of the said recess by the lever 11 by means of a small arm 17, and the clockwork is started. At the same time the escapement-wheel 13 and the disk 3 are turned back one step. If several coins are inserted successively into the clock, the recess 5 will obviously be moved back as many teeth 22 as the number of the coins inserted.

If the coupling mechanism is so arranged that the wheel 13 is turned forward one tooth for instance each week, the clockwork can, after proper winding up, be kept going a week for each coin inserted. As the number of teeth 22 is considerably greater than the greatest number of coins likely to be inserted successively, there is hardly any risk of the disk being turned back a whole revolution and thus being carried back to the starting-point. In order to exclude this possibility, a pin 25 (Fig. 3), for instance, may be applied to the disk 3, which pin, by engaging the end 8 of the lever 7, prevents the disk from being turned back to the starting-point, so that the disk 3 is stopped in the back-movement before it has been turned back a whole revolution. The toe 15 cannot then be moved aside sufficiently to let the next coin pass, but the coin remains until the clockwork has moved the disk 13 at least one tooth forward.

The invention may, of course, vary in many respects. Instead of using a friction coupling between the disk 3 and its driving wheel 21, the disk can be made to rotate backwards freely, but positively movable with the wheel 21 by means of a chick-wheel or the like. Further, the lever 7 may be

arranged in such a way, that it is held out of engagement with the balance by means of a spring and brought into engagement with the latter by means of a pin or the like on a disk, arm, or the like, corresponding to the disk 3.

For the use of different sizes of coins, the front wall 24 of the chute 1 may be made adjustable transversely of the chute.

According to the invention the clockwork can also be combined with a counting-device for the purpose of indicating how many coins inserted at different times within a given period remain before the clock-work is locked. This can be done in a most simple way by combining the counting device and the coupling mechanism 13, 3. The counting device consists of a disk 26, which participates in the turning of the wheel, and which is provided with figures from zero up to the number of teeth of the wheel 13, so that a figure (number) becomes visible for each tooth, i. e. for each step, which the wheel 13 is moved forwards. When the clockwork is shut off, the zero is visible in the opening 28, as shown in Fig. 2. When the coins then are inserted, the figure (number) in the opening becomes higher and higher, thus showing how many coins have been inserted successively. Later on, during the normal running of the clock, there may be read off in the opening how many coins remain for the clock to consume before the clockwork is shut off.

Having now described our invention, what we claim as new and desire to secure by Letters Patent is:

1. In coin controlled savings clocks including a casing containing a clockwork and a coin chute, the combination of a driving wheel forming part of the clockwork, a disk frictionally coupled to said driving wheel, means engageable with said disk and a part of said clockwork for locking said disk and said clockwork against movement, a pivotally mounted lever having a portion projecting into the chute and engageable by a coin descending in said chute to rock said lever, and means carried by said lever to actuate the first named means to release the clockwork and free said driving wheel for rotation.

2. In coin controlled savings clocks including a casing containing a clockwork and a coin chute, the combination of a driving wheel forming part of the clockwork, a disk frictionally coupled to said driving wheel, a lever having one arm engageable with said disk and another arm engageable with a part of the clockwork for locking the disk and clockwork against movement, a second pivotally mounted lever having a portion projecting into the chute and engageable by a coin descending in said chute to rock said second lever and means carried

by said first lever for, respectively, positively reversely rotating said disk and actuating the first named lever to release the clockwork and free said driving wheel for rotation.

3. In coin controlled savings clocks including a casing containing a clockwork and a coin chute, the combination of a driving wheel forming part of the clockwork, a peripherally recessed disk frictionally coupled to said driving wheel, a lever having one arm engageable with the recess in the disk and another arm engageable with a part of the clockwork for locking the disk and clockwork against movement, a gear wheel rigid with said disk, a second pivotally mounted lever having a portion projecting into the chute and engageable by a coin descending in said chute to rock said second lever, means carried by said second lever to move the arms of the first lever out of engagement with the part of the clockwork and the recess in the disk and means carried by said second lever for engaging said gear wheel reversely rotating said disc.

4. In coin controlled savings clocks including a casing containing a clockwork and a coin chute having an aperture in a wall thereof, the combination of a shaft carrying a driving wheel forming part of the clockwork, a disk on said shaft frictionally coupled to said driving wheel, said disk having a recess in its periphery, a ratchet wheel on said shaft rigid with the disk, a lever having one arm provided with an extension for entering said recess and another arm provided with an extension for engaging a part of the clockwork whereby when said extensions are in engagement with their co-relative parts the clockwork and disk are locked against movement, a second pivotally mounted lever having a toe extending through the aperture in the chute wall into the path of coins descending in said chute, a pawl carried by said second lever and adapted to engage said ratchet wheel to reversely rotate said disk and an arm projecting from said second lever and adapted to move the extensions of the first lever out of engagement with the disk and clockwork.

5. In coin controlled savings clocks, the combination with the elements claimed in claim 8, of a pin projecting from the periphery of the disk adjacent the recess therein and adapted to be engaged by one of the extensions of the first named lever to prevent excess reverse rotation of the disk.

In witness whereof we have hereunto signed our names.

A. T. HAMMARSTRAND.
